UNITED STATES PATENT OFFICE.

WILLIAM D. FULLER, OF SPRINGFIELD, OHIO, ASSIGNOR TO THE LAGONDA MANUFACTURING COMPANY, OF SPRINGFIELD, OHIO, A CORPORATION OF OHIO.

TUBE-CLEANER.

1,147,230.

Specification of Letters Patent. Patented July 20, 1915.

Application filed April 5, 1913. Serial No. 759,197.

To all whom it may concern:

Be it known that I, WILLIAM D. FULLER, a citizen of the United States, residing at Springfield, in the county of Clark and State 5 of Ohio, have invented certain new and useful Improvements in Tube-Cleaners, of which the following is a specification, reference being had therein to the accompanying drawings.

10 My invention relates to tube cleaners and more particularly to a rotary cleaner having a swinging tool or tools acting by centrifugal force.

My invention contemplates a device for 15 the cleaning or dislodging of scale or other deposits from the exterior as well as the interior of tubes, and is especially adapted for cleaning boiler tubes, although it may be used for other purposes.

20 The object of my invention is to provide an improved cleaner of few parts, simple, strong and durable that can be readily assembled and easily taken apart, the parts being so associated in their operative relation as to give the greatest efficiency.

In devising a cleaner the problem is presented of providing a device of such limited dimensions as to operate within a tube and yet give to the tool or tools sufficient action 30 as to efficiently do the work. This I have accomplished by providing a rotary body having pivoted thereto a single arm swinging alone in a given plane so as to cut the axis of the body; said arm having pivoted 35 thereto upon a single pivot a tool or tools adapted to swing across the axis of the body.

It will be seen that by the use of a single arm in a given plane unobstructed by other 40 arms operating in the same plane the arm can be given a greater length or throw to increase the force and efficiency of the tool it carries; and further the use of a single arm in a given plane instead of a plurality 45 of arms each having a tool pivoted thereto permits the employment of a tool or tools of relatively large dimensions pivoted to a single pivot on said arm to swing across the axis of the body, whereby additional force 50 is given to the blow delivered by the tool or tools. Furthermore in this construction the arm and tool are not only given a greater radial throw; but by reason of their increased dimensions, made possible by their

novel arrangement and coöperation, the arm 55 and tool or tools can be made heavier, which not only increases the force of their action but adds greatly to their strength and durability.

The arm may be limited to swing into 60 operative position on one side only of the cleaner; but I preferably arrange it to swing into operative position on opposite sides, for this not only increases its efficiency, but permits its use with a right or left hand 65 drive.

My invention contemplates and the use of the term tool or tools includes any form of a hammering or cutting tool pivoted to swing across the axis of the body of the 70 cleaner by a dual swinging movement such as I have described.

The tool may be in the form of a disk having a plain or toothed periphery; or it may be made cone-shaped with peripheral 75 teeth. But I preferably employ a plurality of tools pivoted to a single pivot and spaced apart in the plane of their movement so that like a wagon wheel without its felly each tool will strike and rebound giving it a very 80 forceful and efficient hammering or hammering and cutting action.

In the development of my invention I tried out the device with a single and various numbers of tools and while I obtained 85 the best results with three and four tools spaced apart as stated, I do not wish to be understood as limiting myself to any particular number.

The tools may have plain surfaces to act 90 as hammers or they may be formed with teeth to cut as well as hammer; and for use in light scale rotating cutters pivoted to the tool may be employed. These and other features of my invention will be disclosed 95 in the constructions and combinations hereinafter more particularly described and set forth in the claims.

Referring to the accompanying drawings Figure 1 illustrates one form of my cleaner 100 shown attached to a motor and disposed within a tube. Fig. 2 is an end view of the cleaner with the tool centrally disposed in its relation to the body. Fig. 3 is a section on the line 3—3 of Fig. 2. Fig. 4 is an end 105 view of the cleaner with the tool at the extreme limit of its throw to one side of the body and Fig. 5 is a like view with the tool

at the extreme limit of its throw to the opposite side of the body. Fig. 6 is a section on the line 6—6 of Fig. 7 showing a plurality of cutter wheels on the tool. Fig. 7 is a section on the line 7—7 of Fig. 6. Fig. 8 is an end view of a tool formed as a cone cutter. Fig. 9 is a section on the line 9—9 of Fig. 8. Fig. 10 is an end view of a tool in the form of a plain disk. Fig. 11 is a section on the line 11—11 of Fig. 10. Fig. 12 is an end view of a tool in the form of a toothed disk. Fig. 13 is a section on the line 13—13 of Fig. 12. Fig. 14 is an end view showing a plurality of tools joined to a single hub. Fig. 15 is a side elevation of Fig. 14. Fig. 16 shows a recess to limit the operation of the tool to one side and Fig. 17 a like view showing recess to limit the operation of the tool to the opposite side.

Like numerals represent the same parts in the several views.

In the drawings 1 represent a tube in which there is disposed in operative position, a rotary motor 2 which may be of any suitable construction, having a supply conduit 3 and a shaft 4. A body 5 having a screw-threaded opening 6 to secure the same to the shaft 4 is provided on its opposite side with a recess 7 in which an arm 8 is pivoted to swing on a pin 9, preferably formed integrally therewith, journaled in an opening in said body and held in place by a nut 10 which is secured against being jarred loose by a cross-pin 11.

Tools 12 spaced apart and preferably joined integrally with a hub 13 as shown, swing upon a pivot pin 14 secured within an opening *a* in the free end of the arm 8 by a cross-pin 15 extending through an opening *b* in said arm and pin. The pin 14 is provided with a head 16 to hold the tools in place; and the cross-pin 15 is provided with a head 17 seated in a recess of the arm 8 and abutting the wall of the recess 7 whereby said cross-pin is held in place.

The side walls of the recess 7 limit the movement of the arm 8; and in Figs. 2, 4 and 5 this recess is shown of such dimensions that the tools will swing into operative position on opposite sides of the body whereby the cleaner may be driven with either a right or left hand drive, and the maximum throw with the greatest force to the blow of the tools is given. In Fig. 16 the recess 7^a limits the throw of the tools into operative position on one side only of the body; and in Fig. 17 the recess 7^b limits the throw of the tools to the opposite side; but as heretofore stated and for the reasons given the recess 7 of Figs. 2, 4 and 5 is the preferred form.

To assemble the cleaner, the tool is placed upon its pivot pin, the pin is then inserted in the opening *a* of the arm 8, the cross-pin

15 is then inserted, the arm 8 is then placed in the recess 7 with its pivot pin 9 extending through the opening in the body where it is secured by the nut 10 and the cross-pin 11.

It will be understood that the form or type of the tools employed may be varied to suit the character of the work; and with that end in view, while the pin upon which the tools swing may be varied to adapt it to the particular tool, that portion which projects into and is secured in the opening *a* of the arm 8 is of uniform size to fit said opening and is provided with an opening *b* for the cross-pin 15, so that one type of tools may be substituted for another as may be desired.

In Figs. 14 and 15 cutting tools 12^a are pivoted to swing upon a pin 14^a secured in the opening *a* of the arm 8 in like manner as the tools 12 as heretofore described.

In Figs. 6 and 7 the tool 18 is shown with recesses 19 in each of which there are pivoted on pins 20 a plurality of cutter wheels 21, said pins having enlarged ends 22 screw-threaded into an opening in the tool as shown, and held from jarring loose by a wearing plate 23. Said tool is pivoted to swing on a pin 24 having a reduced end 24^a of a size to fit the opening *a* of the arm 8 and provided with an opening for the cross-pin 15 and secured in like manner as heretofore described.

Figs. 8 and 9 disclose a cone cutting tool 25 pivoted on a pin 26 having a reduced end 26^a suitable to be secured in the opening *a* of the arm 8 as heretofore described.

Figs. 10 and 11 show a plain disk 27 pivoted on a pin 27^a suitable to be secured in the opening *a* of the arm 8 and Figs. 12 and 13 disclose a cutter disk 28 pivoted on a pin 28^a suitable to be secured within the opening *a* in the arm 8 as heretofore described.

The tools with cutting teeth are especially adapted for use in cleaning scale from the interior of water tubes, while those having plain surfaces are employed in fire tubes to dislodge by their hammering action the scale adhering to the outside surface of the tubes, although they will give efficient service in cleaning water tubes.

Having thus described my invention I claim:

1. In a tube cleaner, a rotary body having a single transversely extending arm in front of said body pivoted at one end thereto and proportioned to swing upon its pivot across the longitudinal axis of said body and a tool or tools in front of said arm carried by the free end thereof, substantially as described.

2. In a tube cleaner, a rotary body having a single transversely extending arm in front of said body pivoted at one end thereto and a tool or tools in front of said arm pivoted to the free end thereof, said tool or tools be-

ing proportioned and said arm free to swing said tool or tools in position to turn upon their pivot across the longitudinal axis of said body, substantially as described.

5 3. In a tube cleaner, a rotary body having a single transversely extending arm in front of said body pivoted at one end thereto and a tool or tools in front of said arm pivoted to the free end thereof, said arm and tool or 10 tools each being proportioned and free to move upon their respective pivots across the longitudinal axis of said body, substantially as described.

4. In a tube cleaner, a rotary body having 15 a single transversely extending arm in front of said body pivoted at one end thereto and tools spaced apart and terminating in a central hub in front of said arm pivoted to the free end thereof and proportioned to turn 20 upon their pivot across the longitudinal axis of said body, substantially as described.

5. In a tube cleaner, a rotary body having a single transversely extending arm in front of said body pivoted at one end thereto and a tool having rotary cutters pivoted thereto in front of said arm, said tool being pivoted to the free end of said arm, said arm being free to swing said tool in position to

turn upon its pivot across the longitudinal axis of said body, substantially as described. 30

6. In a tube cleaner, a rotary body adapted to be secured to driving means and having a triangular recess in its forward face extending in a plane transverse to the axis of said body, an arm pivoted to swing within said 35 recess and be protected thereby, and a tool or tools pivoted to said arm, substantially as described.

7. In a tube cleaner, a rotary body adapted to be secured to driving means and having a 40 recess in its forward face with an arm therein extending transversely to the axis of the body and pivoted at one end thereto to swing by centrifugal force, a tool and a pivot therefor, a cross-pin to hold said pivot within an opening in the free end of said arm, said cross-pin being retained in place by a wall of said recess, substantially as described. 45

In testimony whereof I have hereunto affixed my signature in the presence of two witnesses.

WILLIAM D. FULLER.
